UNITED STATES PATENT OFFICE.

ROSANA DU FORA ULMAN, OF CHICAGO, ILLINOIS, ASSIGNOR TO ANNA ROTHSTEIN, OF CHICAGO, ILLINOIS.

GARMENT.

Application filed August 4, 1926. Serial No. 127,016.

This invention relates to garments such as girdles, girdle-brassières, and the like.

It is an object of this invention to produce in a garment of the kind mentioned a construction especially suited for stout figures. It is highly desirable that such a garment provide the proper support for the abdomen, that it be comfortable when worn upon the figure, and that it repress or confine any bulging tendency on the part of the figure which should preferably be concealed.

In the attainment of these objects, I provide a garment structure which is simple, inexpensive to manufacture, and easily fastened upon the body. It includes among other components an elastic section extending across the front of the abdomen, and protected both to the front and rear sides thereof by fabric which is relatively inelastic. In addition, reinforcing stays may be associated with one of the protecting fabric sections, all as will appear from the description to follow.

These and other objects of my invention are realized in the illustrative garment shown in the accompanying drawing in the manner following:

Figure 1 is a perspective view of the garment partly fastened upon the figure;

Fig. 2 is a plan or development view of the garment, looking upon its inner side;

Fig. 3 is an enlarged detail in transverse section, taken on line 3-3 of Fig. 1; and

Fig. 4 is a top plan view showing the abdominal flap which is illustrated in Fig. 2.

The illustrative garment is of the combination type, in that its upper and lower portions constitute respectively a brassière and a girdle. I wish it understood, however, that the improved features of this invention may be embodied in a girdle which is independent of any associated part, such as a brassière. Any suitable material, or combinations of materials, may be used in producing such a garment, the components of which are suitably cut and assembled together to make a proper fit upon the figure.

As shown, the garment is provided with front and back sections A and B, respectively, connected by one or more side sections C wherein may be interposed portions 7 of elastic material of any desired size and form. The front section A of the garment

co-operates with an adjacent section 8, the one being fastened to the other along the 55 side front as by means of the usual hooks and eyes 9 and 10, respectively. These or any equivalent fastening devices may be applied to the free edges of the two garment sections in any approved manner, as by having the same carried on reinforcing tapes 11 in a well known manner. The particular location of the opening between the sections may be varied, however, it being optional whether it be more to the front or to the 65 side.

Upon the inner side of the garment so formed are two flaps 14 and 15 having their rear edges secured adjacent the sides of the garment. With the flap 14 is associated an 70 extension piece 16 having a duplex connection therewith. This connection consists in part of an elastic section 17, the side edges 18 of which are secured to the flap 14 and extension 16 at points relatively remote from 75 their proximate edges 19. In this manner the two edges 19 are normally held in closely adjacent relation by the elastic section. The connection also consists in part of a fabric backing 20 joined to the flap 14 and extension 16 at or near the side edges 18 of the elastic section 17, and folded vertically upon itself, as at 21, to provide a pleat. If desired, reinforcing stays 22 may be carried by the flap and extension piece in the manner 80 best shown in Fig. 2.

The flap 14 is associated with the outer garment section A, and together with the extension piece 16 extends substantially across the front of the abdomen so as to 90 present its free edge 23 to the side front thereof. In like manner, the free edge 24 of the flap 15 terminates adjacent to the edge 23 so as to fasten thereto with the aid of appropriate devices, such as hooks and eyes, as shown.

In the application of such a garment to the body, the inner flaps are first drawn together and fastened. These flaps co-operate with the rear portion of the garment in 100 encircling the abdominal region to provide a girdle. On account of the elastic section 17 this girdle may fit snugly, yet without discomfort. The outer sections A and 8 are 105 then brought together and fastened around the inner girdle portion, the presence of

which is thereby concealed. On account of the elastic character of the inner girdle portion, the garment may yield as required in response to the movements or changes in the 5 position of the wearer.

I would have it noted that the elastic section 17 does not touch the body at any point. It is protected by the pleated backing which definitely limits the stretch of the elastic. 10 It is preferred that the backing should be cut lengthwise so as not to stretch after the elastic has reached its limit of expansion. To the front of the elastic section is the flap 14 and extension piece 16 wherein may 15 be carried suitable reinforcing stays. In addition, the outer garment sections A and 8 overlie the flaps so as to conceal the presence of the stays, or any protuberance of the body against which the stays may exert 20 pressure. Such a structure provides a yielding confinement of the body. It is therefore seen that the present garment provides a smooth flap abdominal support the presence of which is at all times concealed.

25 I claim:

1. A garment of the kind described adapted to encircle the figure, inner flaps extending toward the front of the figure with their edges secured to the garment adjacent the 30 sides thereof, an extension piece detachably fastened to one flap, means securing the extension piece to the other flap comprising an elastic section joined thereto at points remote from the proximate edges of the flap and extension piece, and a backing for the elastic section joined to the flap and extension piece at points close to the side edges of the elastic, the backing having a vertical pleat whereby it may expand within definite 35

limits as the elastic is stretched, substantially 40 as described.

2. A garment of the kind described adapted to surround the figure, and having an opening toward the front thereof with means for detachably connecting the garment portions adjacent said opening, an abdominal support carried by the garment and consisting of two flaps each joined thereto, and an extension piece joined to one flap and adapted for detachable connection with 45 the other flap, the extension piece and associated flap being slightly separated and being associated with an elastic section connected thereto at points remote from their proximate edges, there being also an inelastic fabric backing with a pleat therein lying between the elastic section and the figure, the garment when fastened about the figure lying to the front of the abdominal support, substantially as described. 50

3. A garment of the kind described adapted to surround the figure having an associated abdominal support comprising a flap and extension piece one joined yieldingly to the other centrally of the figure, the flap being fastened to the garment and, together with the extension piece, lying across the front of the figure, a second flap also joined to the garment and connecting detachably to the extension piece, vertical reinforcements carried by the flap and extension piece, a pleated backing connecting said flap and extension piece, and an elastic section also connecting said flap and extension piece and lying between these parts and the backing, substantially as described. 55 60 65 70 75

ROSANA DÜ FORA ULMAN.
